US0D1040023S

(12) **United States Design Patent** (10) Patent No.: **US D1,040,023 S**
(45) Date of Patent: ** Aug. 27, 2024

(54) **MOTOR VEHICLE AND/OR TOY REPLICA THEREOF**

(71) Applicant: **TOYOTA JIDOSHA KABUSHIKI KAISHA**, Toyota (JP)

(72) Inventors: **Byung Hyun Yoo**, Irvine, CA (US); **Alexander Wen Shen**, Fullerton, CA (US)

(73) Assignee: **TOYOTA JIDOSHA KABUSHIKI KAISHA**, Toyota (JP)

(**) Term: **15 Years**

(21) Appl. No.: **29/841,177**

(22) Filed: **Jun. 3, 2022**

(30) **Foreign Application Priority Data**

Dec. 7, 2021 (JP) ..... 2021-026889 D

(51) **LOC (14) Cl.** **12-08**

(52) **U.S. Cl.** **D12/92**
